UNITED STATES PATENT OFFICE.

CHARLES U. CARPENTER, OF MIAMISBURG, OHIO, ASSIGNOR TO FIRE-PROOF FURNITURE AND CONSTRUCTION COMPANY, OF NEW YORK, N. Y., A CORPORATION OF NEW YORK.

FIREPROOF SAFE.

1,116,382.

Specification of Letters Patent. Patented Nov. 10, 1914.

Application filed November 16, 1911. Serial No. 660,613.

To all whom it may concern:

Be it known that I, CHARLES U. CARPENTER, a citizen of the United States, residing at Miamisburg, in the county of Montgomery and State of Ohio, have invented certain new and useful Improvements in Fireproof Safes, of which the following is a specification.

Fireproof safes have heretofore usually been made with a stepped cast-iron framing for forming the door-jamb, the door being made with a coacting stepped cast-iron framing received within the stepped cast-iron framing of the door-jamb when the door is closed, flat plates being riveted to the outer faces of these framings for forming filling cavities respectively in the body and the door, these cavities being usually filled with a hydraulic cement compound as a fire-proofing filling. In practice these stepped cast-iron framings when being cast, warp out of their true shapes in the act of cooling, owing to molecular strains. In order to use these castings, it has been found necessary in practice to reshape them into their true shapes, and this is done by peening or hammering or stretching the metal where the cast framing is out of shape. It has been further found in practice that if a safe, the framings of which have been so stretched, is subjected to fire, the heat will cause the molecules of the castings to reassume their original relations and will rewarp the framings to practically the shapes they had when they were originally cooled after their casting, thereby forming cracks or openings in the joint between the door and jamb, especially at the corners of the door, admitting the heat of the fire into the interior of the safe and often destroying its contents. It has been further found in practice that the heat of the fire will attack the rivets, which secure the outer plates to the outer faces of the framings at the front thereof, loosening the same and the plates, the plates warping and curling away from the framings at the edges of the plates, thereby providing openings for the admission of heat into the interior of the safe, and also permitting the safe-filling to rapidly deteriorate when subjected to water with the

heat, the filling crumbling and leaking between the crevices formed between the edges of the framings and the plates, by the curling of the edges due to heat and the alternate heating and cooling when subjected to fire and water. It has been further found in practice that the stepped cast-iron framings are very liable to break, and do break, especially in the case of the falling of the safe for instance, in the collapse of the floor upon which the safe is located, or in the falling of a heavy body upon the safe. It has been further found in practice that when the usual hydraulic cement compound has been employed as a fire-proofing material, steam is generated when the safe is subjected to fire, owing to the fact that the cement contains a large percentage of water, the steam aiding in displacement of the plates secured to the framings and also filling the interior of the safe and damaging its contents.

It is the object of the present invention to provide a fireproof safe in which these objections are avoided, and the invention consists in providing a front structure which has rearwardly bent integral edges at the joint between the door and safe body; further in providing securing means between said rearwardly bent edges and a stepped framing which are located in the transverse plane of said joint for removing said securing means from contact with fire about the safe; further in providing a front wall for a safe door having integral flanges located between the body of the door and the door-jamb when the door is closed; further in providing a stepped door-jamb and front for the body of the safe which are integral with each other; and further in providing an integral sheet metal stepped framing for a safe structure employed in forming the joint between the door and jamb; and the invention will be further readily understood from the following description and claims, and from the drawings, in which latter:

Figure 1 is a vertical cross-section of my improved device taken on a line corresponding to the line 1—1 of Fig. 3. Fig. 2 is a vertical cross-section of the same

taken on a line corresponding to the line 2-2 of Fig. 3. Fig. 3 is a horizontal cross-section of my improved device, taken on the line 3-3 of Fig. 2. Fig. 4 is a vertical cross-section of my improved device partly broken away, taken on a line corresponding to the line 4-4 of Fig. 3. Fig. 5 is a sectional detail on a line similar to the line 3 of Fig. 2, showing the front door member riveted to the stepped framing of the door. Fig. 6 is a horizontal cross-section taken on a line similar to the line 3 of Fig. 2, but showing my invention employing a pair of doors, instead of a single door as shown in Fig. 3. Fig. 7 is a cross-section on the line 7-7 of Fig. 8, showing a preferred form of cellular heat-insulating body. Fig. 8 is a longitudinal section taken on a line corresponding to the line 8-8 of Fig. 7, showing a section of said cellular heat-insulating body and means for closing the air-chambers therein. Fig. 9 is an enlarged detail showing one side of the safe, partly broken away, and shown in section on a line corresponding to the line 3-3 of Fig. 2. Fig. 10 is a front elevation of the jamb-framing, partly broken away, showing the integral corner construction. Fig. 11 is a rear elevation of the door framing, partly broken away, showing the integral corner construction. Fig. 12 is a perspective view of one of the integral front corners of the body of the safe, with the insulation removed; and, Fig. 13 is a perspective view of one of the integral corners of the door of the safe, with the insulation removed.

11 represents the body of the safe and 12 the door thereof. The door comprises a stepped joint-framing 13 shown as having a series of steps 14. The stepped joint-framing, in the preferred embodiment of the invention is formed up out of sheet metal, preferably high tensile steel, being preferably an integral framing suitably formed to shape, although in practice the sides, top and bottom of the framing are preferably bent into stepped form cross-sectionally, as shown by the steps 14, the corners 15 thereof mitered and solidly 50 integrally welded as by electricity, or the oxy-acetylene flame, as indicated at 24, (see Fig. 13) for forming a one-piece framing.

The frame although light in weight, is by its form and the fact that it is made of sheet metal, preferably high tensile steel, and integral, of great strength, the steps 14 thereof formed from sheet metal giving great rigidity to the framing in all directions, preventing warping thereof if subjected to heat, and providing great strength for maintaining the form of the framing under the various conditions of use or accident in case of fire.

16 is a front wall of the door. It is provided with integral rearwardly turned

flanges 17 at the edges thereof, as at the sides, top and bottom thereof, the corners 18 of the flanges 17 preferably being formed integral or integrally connected as by solid welding. This front wall is formed of sheet metal, preferably high tensile steel, and the stepped framing 13 and flanges 17 are arranged to be secured together in suitable manner, the framing being shown received within the space formed by the flanges.

In Fig. 5, the framing and flange are shown secured together by rivets 19, or the same may be connected together by means of solid welding for forming the flange integral with the framing as shown at 20 in Figs. 3, 9 and 13.

The front wall is reinforced by the rearwardly extending flange located thereabout and prevented from curling outwardly thereby, and the joint between the door and jamb is preserved in case of fire, and if rivets, bolts or screws are employed between the rearwardly extending flanges and the stepped framing, they are removed from the direct action of the heat of a fire, and the dropping out or removal of the said rivets, bolts or screws is prevented by being held in place between the door and door-jamb, they thereby continuing to serve their functions of holding the flange and front wall in place even if they should become loosened in the course of a fire. The construction prevents warping of the parts.

The inner wall of the door may be formed by a plate 21 suitably secured to the lateral inner flange 22 of the door framing, as by being riveted thereto by rivets 23, or if desired by spot welding.

31 is a jamb framing formed up of sheet metal, preferably high tensile steel, and in the preferred embodiment of the invention is an integral sheet metal framing comprising corners 32. It preferably comprises the front wall 33 and the stepped jamb 34 and may also include an outer rearwardly projecting flange 35, these parts being preferably formed up integral with each other. The sides, top and bottom of the framing may be made integral with each other, or the corners thereof mitered and integrally formed by solid welding, as by electricity or the oxy-acetylene flame, as shown at 26, (see Fig. 12), and form an integral channelled frame-part having an opening 36 of polygonal or other form to correspond to the form of the door, and a channel 37. The stepped jamb comprises the steps 38, a series of these steps being shown which coat with the series of steps 14 of the door at 125 the joint between the door and door-jamb, for forming a close joint between the same, when the door is closed, which is off-set at a plurality of points between the outside and the inside of the safe, these off-sets acting as 130

sheet baffles for heat in case of fire for retarding admission of heat into the interior of the safe.

41 represents the outer casing of the safe body, and 42 the inner casing thereof. The lateral wall 43 of the outer casing, which preferably includes the sides, top and bottom, is formed with an inwardly extending flange 44 at its front and an inwardly extending flange 45 at its rear, these flanges serving to strengthen the lateral wall of which they form a part, this lateral wall being of sheet metal, preferably of high tensile steel, with the inwardly extending flanges bent integrally therefrom, and having its corners solid welded, as shown at 27. The front portion of the lateral wall is received in the channel 37 of the channeled frame-part and suitably secured to the rearwardly projecting flange 35 as by solid welding shown at 47.

The rear of the outer casing of the safe is preferably formed by a rear wall 51 of sheet metal, preferably high tensile steel, having an inward reinforcing bulge 50. Its edges are bent forwardly in the form of integral forwardly extending flanges 52 which are also integral at the corners thereof, and preferably form a lid-like container in which the rear end of the lateral wall is received, the same being secured to said lateral wall, as by means of solid welding 53. Angle-strips 54 are preferably secured to the lateral wall at the corners thereof, as by solid welding, shown at 55.

58 is an inner lateral wall for the inner casing and is formed up out of sheet metal, preferably high tensile steel, with integral laterally extending flanges 59 received against the inner flange 60 of the jamb framing, to which they are secured for instance by rivets 61. 65 is a rear wall for the inner casing also formed up out of sheet metal, preferably high tensile steel, and has integral rearwardly extending flanges 66 formed up therefrom, these flanges being secured to the lateral inner wall as by rivets 67.

71 is a cavity in the door, and 72 is a cavity in the body. The cavity in the body preferably surrounds the inner casing.

Fireproofing means for the door may be provided, if desired, and comprise a body 73 of insulating material. This body of insulating material is spaced from the front wall of the door by a space 78 and is preferably spaced from the rear wall of the door by a space 79. Each of these spaces is preferably a dead air chamber. The body 60 of fireproofing material preferably extends into that transverse projection of the steps of the door-framing which extends at right angles to the face of the door, and preferably separates the dead air chambers 78, 79.

The body of the safe may be provided, if desired, with preferably similar fireproofing arrangement. Thus 81, 81, are bodies of fireproofing material between the sides of the inner and outer casings of the body, and 82, 83, are bodies of fireproofing material respectively between the tops and between the bottoms of the inner and outer metal casings. 84 is a body of fireproofing material between the rear walls of the inner and outer metal casings. These bodies, 81, 82, 83 and 84, of fireproofing material are preferably connected together at their adjacent edges in suitable manner, as by connections 85, for forming a heat-insulating casing between the outer and inner metal casings of the safe-body, which may be held in place, for instance, by suitable props 86, 87. The front edges of the bodies of fireproofing material received about the lateral wall of the inner metal casing, preferably extend into the channel of the front framing of the body.

An outer air chamber 89 is formed between the outer metal casing of the safe-body and the bodies of fireproofing material therein, this air chamber being preferably a dead air chamber, by being closed at its edges, and an inner air chamber 90 is preferably formed between the fireproofing material in the body and the inner metal casing. This air chamber is also preferably a closed or dead air chamber. The air chambers are preferably separated from each other for preventing circulation of air from one to the other, the bodies of heat-insulating material preferably forming these separating mediums.

When the door is closed, the body of fireproofing material in the door is preferably received between the forward ends of the bodies of fireproofing material between the inner and outer metal casing of the safe-body.

The dead air chambers form heat-insulating mediums which retard the transmission of heat, for instance from the outer metal wall α to the heat-insulating material, the function of which is to avoid concentration of intense heat at particular points of the insulating body, thereby preventing its being punctured or disintegrated, and a similar heat-retarding effect is produced between the insulating body and the inner casing or wall of the safe structure.

The bodies of fireproofing material preferably comprise a cellular structure, consisting preferably of corrugated sheets 91, for instance, of asbestos, received between and secured by connections 88 to flat sheets 92 of asbestos, for forming air cells 93 which are closed at their ends, as shown by the closures 94, suitably secured thereto, for preventing circulation of air through said cells, forming dead air cells. The sheets 91 and 92

92 are preferably secured together at their meeting points.

A suitable locking mechanism may be employed for locking the door in place, but this 5 is not more particularly shown, as any well known locking mechanism may be employed for the purpose.

In Fig. 3 a construction is shown in which 10 a single door is employed to close the door opening. If it is desired to employ a double door for the purpose, the door joint between the doors may be in stepped form, as shown in Fig. 6, by the mating portions 95, 96, respectively provided with a series of steps 15 97, 98, the other elements of the doors corresponding to similar elements thereof, shown in other figures, being indicated by similar but primed reference numerals. These mating portions are formed up out of 20 sheet metal, preferably high tensile steel, and may be integral with the tops and bottoms of the door framings by being formed in one piece therewith or being welded thereto.

25 Having thus fully described my invention, what I claim as new and desire to secure by Letters Patent, is:

1. In a fire-proof safe, the combination 30 of a safe body having a door-opening, and a safe door arranged to be received in said opening, said safe door comprising a stepped joint-framing and a front wall having its edges bent rearwardly and formed as an integral flange which is integral with said 35 front wall, the wall of the outer step of said stepped joint-framing and said flange sloping parallel to each other rearwardly toward the center of the door, said flange and said wall of said outer step of said stepped 40 joint-framing welded together as an integral structure and located between the walls of said door-opening when said door is closed, substantially as described.

2. In a fire-proof safe, the combination 45 of a body having a door-opening, and a fire-proof door comprising a sheet-metal joint-framing and a sheet-metal front wall provided with a rearwardly extending flange integral therewith, the said flange and joint-framing lapping each other and secured together for forming a rearwardly extending lapped joint located in said door-opening and protected by the wall of said door-opening when said door is closed.

55 3. In a fire-proof safe, the combination of a safe body having a door-opening formed by a stepped wall, and a safe door comprising a sheet-metal stepped joint-framing, the sides, top and bottom whereof 60 respectively have joint-steps bent integrally therein, the said sides, top and bottom being heat-welded together at their adjacent ends for forming said integral sheet-metal stepped joint-framing, and a sheet-metal front wall provided with an inwardly ex-

tending flange integral therewith and lapping the outer end of said joint-framing, the said flange and outer end of said joint-framing being secured together and forming a rearwardly extending lapped joint located in said door-opening and protected by the wall of said door-opening when said door is closed.

4. In a fire-proof safe, the combination 75 of a safe body comprising an integral high-tensile sheet-steel frame-part surrounding the door-opening and comprising a front wall and a stepped joint-framing integral with each other and having an angle-bend therebetween, and a safe door comprising a 80 stepped joint-framing, and a front wall provided with a rearwardly extending flange bent with an angle-bend integrally therewith and within which flange the outer end of said stepped joint-framing of said door 85 is received and secured, the said flange received within said frame-part, and the angle-bend between said integral front wall and flange of said door being in juxtaposition to said angle-bend between said integral front wall and stepped joint-framing 90 of said body when said door is received in said door-opening.

5. In a fire-proof safe, the combination 95 of a stepped joint-framing forming a door-opening and having an inner laterally inwardly extending flange around the wall of said door-opening for forming a casing-receiving opening, an inner casing comprising a wall-framing telescoping through said 100 last-named opening from the front and received in said last-named opening and having a front laterally outwardly extending flange which laps over said laterally inwardly extending flange for being secured thereto, 105 and a rear wall having an edge flange in line with and received telescopingly within said wall-framing.

6. In combination, in a fire-proof safe 110 body, a sheet metal front frame-part formed up with a front wall, a stepped joint-framing at the inner edge of said front wall and a rearwardly extending flange at the outer edge of said front wall, said flange extending around said frame-part as an outer containing wall, a wall-framing the front and rear ends of which are formed with inwardly extending flanges, the front flanged end of said wall-framing received in said containing wall, and an outer rear wall having a surrounding flange integral therewith 115 received about the rear flanged end of said wall-framing.

7. In combination, in a fire-proof safe 120 body, a sheet metal front frame-part formed up with a front wall, a stepped joint framing at the inner edge of said front wall and a rearwardly extending flange at the outer edge of said front wall, said flange extending around said frame-part as an 125 130

outer containing wall, and a wall framing having an integral inwardly extending flange at its front end, said front end and said integral inwardly extending flange received in said outer containing wall and secured rigidly thereto for reinforcing the same.

In testimony whereof, I have signed my name hereto in the presence of two subscribing witnesses.

CHARLES U. CARPENTER.
